D. W. ALLMAN

HORSESHOE

Filed Nov. 15, 1920

Inventor.

David W. Allman

Fig. 3. by H. J. Denison
City.

UNITED STATES PATENT OFFICE.

DAVID W. ALLMAN, OF TORONTO, ONTARIO, CANADA.

HORSESHOE.

Application filed November 15, 1920. Serial No. 424,287.

To all whom it may concern:

Be it known that I, DAVID W. ALLMAN, a subject of the King of Great Britain, and resident of the city of Toronto, in the county of York, the Province of Ontario, in the Dominion of Canada, have invented certain new and useful Improvements in Horseshoes, described in the following specification and illustrated in the accompanying drawings, that form a part of the same.

The principal objects of the invention are, to obviate the objectionable conditions in the fastening of shoes to horses' feet and to provide a form of shoe which will hold securely without requiring the use of nails or without otherwise defacing the hoof.

A further and important object is to facilitate the placing of the shoe upon the hoof and still further to protect the tender portions of the hoof from injury.

The principal feature of the invention consists in the novel construction of a shoe supporting member adapted to be secured to the foot and of the means for fastening said member to the hoof, whereby a plate to which the shoe is fastened is held against the bottom of the hoof by metallic strips and said strips are secured in place by a flexible band encircling the hoof.

In the drawings, Figure 1 is a perspective view of a horse's hoof showing my improved shoe attached thereto.

Fig. 2 is a perspective view of the shoe removed from the hoof.

Fig. 3 is an enlarged longitudinal sectional view of a slight modification in the construction of the member for holding the ends of the flexible connecting member.

Fig. 4 is a rear elevational view of a further modification of means for adjusting the flexible fastening member.

Fig. 5 is a cross-sectional view through the adjusting means illustrated in Fig. 4 showing the supporting bracket and the rear non-slip pad.

The shoe consists of a plate 1 which is formed to the shape of the bottom of the hoof and it is preferably provided with the upturned toe clips 2 at either side of the forward portion.

Slots 3, 4 and 5 are cut through the plate adjacent to the center of the toe and transversely opposite at the sides.

A strip 6 of thin metal the width of the slots 4 and 5 extends across the top of the

plate and through the slots, passing underneath the plate and upwardly at the sides, and said strip is secured by rivets 7 extending through the plate.

A strip 8 of thin metal is secured centrally to the cross strip 6 and extends forwardly of the plate and passes downwardly through the slot 3 and upwardly at the toe of the shoe.

The ends of the strips 6 and 8 are formed with beads 9 in which is inserted a flexible wire 10 which is adapted to encircle the horse's hoof.

At the rear of the plate 1 is secured an angle bracket 11 having a longitudinal passage 12 through which the ends of the wire are threaded. The shoe proper or wearing portion 13 is of the ordinary type of horseshoe and is secured to the plate 1 in any desirable manner by means of rivets, bolts, or screws, and it may be provided with suitable calks 14 for gripping the pavement.

In placing this shoe upon a hoof a shoe is selected to fit the hoof and it is inserted into the loose and open wire loop 10. The horse is then caused to rest its weight upon the shoe and one end of the wire is hooked over one side of the bracket 11. The other end is drawn up tight so as to draw the ends of the strips 6 and 8 tightly into engagement therewith. Then the wire is bent back over the bracket as seen in Fig. 2. It is thus securely held and a shoe cannot become dislodged from the foot but will wear until the bottom portion is worn away and even then the foot will not be exposed.

It will be readily seen that the plate will protect the horse's hoof from injury from stones and other rough obstructions but being open at the back it will not interfere with ventilation and will not injure the foot.

It may be found desirable to allow for expansion in the fastening member and this may be accomplished in a very simple manner, as illustrated in Fig. 3, where the tubular member 15 is formed on the bracket 11 and one end of the wire is hooked around one end of the tube and the other end is passed through a coil spring 16 and secured thereto so that the flexibility of the spring will be the connection between the ends of the wire 10.

In Fig. 4 I show a further modification of this adjustable feature in the form of a

slide-way 17 secured to the back of the bracket, and in this slide-way are arranged a pair of slides 18 having outwardly projecting lugs 19 through which a bolt 20 is inserted. A compression spring 21 is arranged under the nut of the bolt. The slides 18 are secured to the ends of the wire 10 and it will be seen that any desired tension may be placed upon the wire by 10 tightening the bolt.

In Fig. 5 I show a pad 22 of rubber or other non-slipping material secured to the bottom of the plate below the bracket 11, which pad will extend between the heel 15 portions of the shoe 13 and will engage the road surface and prevent the horse from slipping.

A horseshoe such as described is extremely simple and may be readily fitted 20 to horses' feet, and when the shoe is worn it may be easily and quickly removed to have a new facing or wearing portion attached thereto. It dispenses with the use 25 to the horse, both in respect to health and actual wearing conditions.

What I claim as my invention is:—

1. A horseshoe comprising a plate carrying a shoe, flexible metal strips secured to 30 the plate and adapted to embrace the hoof, a flexible band connecting the ends of said strips and adapted to encircle the hoof, and a spiral compression spring arranged between the ends of said flexible band.

35 2. A horseshoe comprising a metal plate carrying a wearing shoe member on the

under side and having slots therethrough adjacent to the sides and to the toe, a flat metal strip extending across the top of the plate and laced through the side walls and 40 extending beneath and upwardly around the outer edge of the plate, a metal strip placed through the front slot of the plate, said strips being adapted to extend upwardly alongside the hoof and having 45 looped extremities, a flexible wire extending through said loops, and flexible means for connecting the ends of said adjustable wire.

3. A horseshoe comprising a plate having 50 flexible strips secured thereto adapted to embrace the hoof, a bracket secured to the back of said plate and having a tubular upper end, a wire adapted to encircle the hoof and secured in the ends of said strips 55 and having its ends overlapping and extending through the tubular portion of the bracket, one end being secured to said bracket, and a spiral compression spring secured in the tubular end of the bracket 60 and engaging the free end of the wire.

4. A horseshoe comprising a plate having metal strips secured thereto and extending upwardly to embrace the hoof, a bracket extending upwardly from the rear 65 of the plate, a flexible wire adapted to encircle the hoof and connecting the ends of said metal strips, means adjustably supported in said bracket connected to the ends of said wire, and resilient means for connecting said adjustable means.

DAVID W. ALLMAN.
